(57) **CLAIM**

The ornamental design for a collapsible feeder, as shown and described.

DESCRIPTION

FIG. 1 is a perspective view of a collapsible feeder in folded, retracted state, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of the collapsible feeder of FIG. 1 in an unfolded, retracted state;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a perspective view of the collapsible feeder in unfolded, expanded state.

The broken line showing of bowl sidewalls in FIG. 15 is illustrative only and forms no part of the claimed design.
